Wichita, Kans. 67207

Filed Sept. 11, 1970, Ser. No. 24,946

Term of patent 14 years

Int. Cl. D28—03

U.S. Cl. D86—10

FIG. 2

FIG. 1 is a perspective view of the cosmetic mirror incorporating my new design which is wall mounted; and

FIG. 2 is a rear elevational view of the mirror and its support frame with a section taken through the support arm along line 2—2.

The opposite side of the support arm is a mirror image, and the back of the wall bracket is flat and unornamental.

I claim:

The ornamental design for a cosmetic mirror, as shown and described.
